METHOD OF MAKING FOOTWEAR

Adolph Martin Mondl, Oshkosh, Wis.

Application February 17, 1941, Serial No. 379,337

3 Claims. (Cl. 12—122)

This invention relates to footwear such as shoes, slippers, or the like, and also to the method of making the same. Although certain features of the invention are applicable to shoes of various kinds, it is particularly directed to those commonly known as play shoes or platform shoes and the construction thereof.

The principal object of the invention is to provide an improved shoe which may be made at a low cost and which will be particularly neat and attractive in appearance.

Other objects are to provide a shoe having a novel form of sole with a finishing band around the lower portion of the shoe; to provide a shoe having a platform covering or band attached to the upper, and enclosing the edges of some of the sole members; to provide an improved method of making footwear of the character set forth; and to provide such other advantages and improvements as will appear more fully from the following description.

In the accompanying drawings illustrating a preferred form of my invention and the method of performing the same,

Fig. 1 is a cross sectional view showing portions of the shoe mounted on a last after some of the operations have been completed;

Fig. 2 is a similar view showing one of the sole members, known as a platform, cemented or attached in position on the inner sole;

Fig. 3 is a similar view showing another step in the method with the shoe substantially completed;

Fig. 4 is a bottom plan view showing the position of certain reinforcing staples;

Fig. 5 is a longitudinal sectional view of a completed shoe; and

Fig. 6 is a side elevation of the same.

As shown in Fig. 1, the upper 10 is applied to the last 11 in the usual manner and drawn tightly over the same with its lower edge 12 extending outwardly around the periphery thereof. A platform covering or band 13 of suitable material is applied around the lower portion of the upper and has an outwardly extending edge or flange 14 which rests on or fits against the edge or flange 12. A lining member commonly known as a sock lining 15, and a doubler or inner sole 16 are then applied to the lower face of the last with their edges extending outwardly to engage with and conform to the shape of the flanges or edges 12 and 14. Staples 17 are then inserted around the edges through the several thicknesses of material in order to hold these parts temporarily together. The shoe is then stitched around the

upper as shown at 18 as close as possible to the side walls of the upper.

A platform 19 of suitable material such as rubber, cork, felt, or the like, is then attached to the inner sole 16 as shown in Figs. 2 and 5 preferably by being cemented thereto around the edge only. After this platform has been applied, the projecting edges of all of the superimposed layers are then trimmed off adjacent to the stitching 18 as indicated by the lines XX. A heel member or wedge 20 of any desired shape and made of any suitable material is then cemented to the platform 19 as shown in Fig. 5.

The upwardly extending portion of the platform covering 13 is then lasted or folded down over the edges of all of the sole members as shown in Fig. 3 and its lowermost edge 21 is turned inwardly under the platform 19 and cemented to the lower face thereof at 22. A filler 23 may then be attached to the lower face of the platform 19 between the inwardly folded edges 21 to take up or compensate for the thickness of such edges, although such filler is not essential in all cases. An outer or main sole 24 is then attached and finished by the regular shoe making process, but is preferably only cemented to the edges 21 of the platform covering as indicated at 25 in Fig. 3.

In some instances, the stitching may be reinforced in various places around the sole by staples 26 which are inserted as close to the stitching as possible. While any number of such staples may be used, I prefer to put about three staples on each side of the shank and one on each side of the toe as indicated in Fig. 4.

It will be particularly noted that the peripheral band or platform covering 13 when applied in the manner described, not only covers the stitching and the edges of the various layers of the sole, but also provides a pleasing and ornamental finish to the lower portion of the shoe. This construction or arrangement also lends to the enhancement of the shoe styling as it permits the use of contrasting colors in a particularly effective manner.

While I have shown a preferred embodiment of my invention and have described the essential steps in the method of making the same, it will be noted that changes may be made in the number or arrangement of the parts and in the various steps of manufacture without departing from the scope of the invention as set forth in the following claims in which I claim:

1. The method of making footwear which includes forming an upper over a last with its lower edge extending outwardly, then applying a

peripheral strip to the upper with its lower edge engaging the lower edge of the upper, then positioning sole members on the last and stapling the outwardly extending edges of the strip, upper, and sole members together, then sewing the edges and sole members adjacent to the upper, then securing a platform to the lowermost sole member, then trimming off said sole members and the platform between the staples and the sewing and closely adjacent to the sewing, then lasting the strip over the edges of all of said members and securing the lower portion thereof to the platform, and then cement attaching an outsole.

2. The method of making footwear which consists in forming an upper, applying a peripheral covering strip around the lower portion of the upper, providing an inner sole which is substantially larger than intended to be when finished, stapling the edges of the strip, the upper, and the inner sole together around the outer periphery of the inner sole, stitching the inner sole to the upper and said covering strip, then applying a platform bottom layer to the inner sole, then trimming off the edges of the peripheral covering strip, the upper, the inner sole and the platform bottom layer adjacent to the stitching and inside of the stapling, then lasting the peripheral strip over the stitching and edges of all of the members and securing it to the lower surface of the platform, and finally securing an outsole to the platform and covering strip.

3. The method of manufacturing stitchdown shoes which consists in lasting portions of the

shoe including an inner sole and an upper on a last, the inner sole being of substantially greater periphery than when finished, and the upper having an outturned margin engaging with the projecting portions of the inner sole, also lasting a platform covering around the sides of the upper, said platform cover having an outwardly extending portion engaging with the projecting margin of the upper and extending to the outer periphery of the insole, the upper and the platform cover being worked in against the sides of the last, then fastening the outer edge of the superimposed portion of the platform cover, the outwardly extending margin of the upper and the insole together by fastening means adjacent to the outer periphery of the inner sole, then sewing a seam through the platform cover, projecting margin of the upper and the inner sole in the angle close to the upper and spaced a substantial distance from the fastening means, then securing a sole layer to the inner sole which is substantially coextensive therewith, then trimming off the outwardly projecting portions of the platform cover, upper, inner sole and sole layer between the fastening means and the seam and adjacent to the seam whereby a relatively narrow projection is left around the upper, then folding the platform cover over the seam and working it down and under the sole layer and fastening it to the lower surface of the sole layer and finally securing an outsole to the inturned portions of the platform cover and to the sole layer.

ADOLPH MARTIN MONDL.
